UNITED STATES PATENT OFFICE.

MILFORD B. FERGUSON, OF BROOKLYN, NEW YORK, ASSIGNOR OF ONE-HALF TO
EDWARD HAAS, OF BROOKLYN, NEW YORK.

WRAPPING MACHINE.

Application filed September 15, 1921. Serial No. 500,744.

To all whom it may concern:

Be it known that I, MILFORD B. FERGUSON, a citizen of the United States, and a resident of the city of New York, borough of Brooklyn, county of Kings, and State of New York, have invented an Improvement in Wrapping Machines, of which the following is a specification.

This invention relates to wrapping machines, and more particularly to that type of wrapping machine in which articles such as cakes of soap, for example, are enclosed in suitable wrappers.

One of the objects of this invention is to provide a wrapping machine of the above type, in which efficient and reliable action is combined with durability of construction and practicability of operation at high speeds.

Another object is to provide a positively acting sheet or wrapper delivering mechanism, by means of which the individual wrappers may be transported to, and positioned with respect to, the wrapping mechanism proper in a reliable manner, and without liability of failure in operation by reason of the varying qualities of wrapping material that may be employed.

This invention aims also to provide a simple and practical mechanism for positively holding the sheets or wrappers as delivered in proper relation to the article so as to insure the proper commencement of the wrapper folding operation.

Another object of this invention is to provide a novel mechanism for handling the articles to be wrapped during the preliminary wrapping operations, and to provide further driving mechanism therefor to make possible higher speeds of operation than have heretofore been obtained in apparatus of this character.

Other objects will be in part obvious or in part pointed out hereinafter.

The invention accordingly consists in the features of construction, combinations of elements and arrangement of parts as will be exemplified in the structure hereinafter described and the scope of the application of which will be indicated in the following claims.

In the accompanying drawings, in which

is shown one of various possible embodiments of this invention.

Figure 1 is a side elevation of a complete wrapping machine; 55

Figure 2 is a vertical section, taken on the line 2--2 of Figure 1;

Figure 3 is a vertical section, taken on the line 3--3 of Figure 2; 60

Figure 4 is a plan view, taken along the line 4--4 of Figure 1;

Figure 4^a is a vertical section taken substantially along the line 4^a--4^a of Fig. 4. 65

Figure 5 is a horizontal section, taken on the line 5--5 of Figure 1, Figure 6 is a like section taken on the line 6--6 of Figure 1, and Figure 7 is a like section taken on the line 7--7 of Figure 1, these figures being sectional views of the sheet or wrapper delivery mechanism; 70

Figure 8 is a horizontal section of the machine, taken along the line 8--8 of Figure 3, and shows in detail certain of the driving mechanisms; 75

Figure 9 is a detached view in side elevation of the article ejecting mechanism and its driving gear, the view showing the several parts in one stage of the operation, and Figure 10 is a similar view showing the several parts during another stage of the ejecting operation; 80

Figure 11 is a detached view in side elevation as seen from the left in Figure 2 of the driving gear for the article handling mechanism, and Figure 12 is a similar view showing the relative positions assumed by the several parts during the various stages of operation thereof; 85

Figures 13, 14 and 15 are detached fragmentary views as seen in Figure 3, illustrating the relations assumed between the wrapper delivery mechanism and the article handling apparatus and associated devices during the successive stages of operation thereof; and 90

Figure 16 is a view in side elevation on an enlarged scale, illustrating the wrapping operation as completed by the operation of the devices shown in Figures 13, 14 and 15. 100

Like reference characters refer to like parts throughout the several views of drawings.

Referring now to the drawings, and more

particularly to Figures 1 to 4, inclusive, it will be seen that I have provided a main frame, comprising preferably the upright standards 20 and 21, to which is rigidly secured in any suitable manner at their upper end a table 22, upon which the several mechanisms may be conveniently mounted. At one end of the table 22 there is provided any suitable mechanism for delivering the articles intended to be wrapped, such as cakes of soap, for example, and in the drawings there is illustrated such a mechanism comprising a conveyor belt 23, carried by a pulley 24, suitably mounted for rotation between a pair of upright posts 25. Two curved guides 26, of angular cross section, as shown in Figure 4, are mounted upon the table 22, and suitably secured at their upper ends to the posts 25, so as to form with the conveyor belt 23 a suitable conduit for conducting the articles carried by the belt 23 in a downward direction, and superimposed one upon the other. A suitable guide plate 27, secured to a standard 28 mounted upon the table 22, is positioned with respect to the conveyor belt 23, and its associated pulley 24, so as to form a complementary part of the guiding conduit for the articles delivered to the machine.

The articles as thus delivered and stacked by the delivery mechanism above described are supported upon the upper surface of a plunger 29 mounted above the table 22 on a pair of guides 30, preferably of circular cross section, and mounted upon the abutments 31 and 32, suitably secured to the table 22. The plunger 29 is adapted to be reciprocated along the guides 30 by means of the lever 33 pivotally mounted at its lower end upon the cross bar 34 suitably mounted in the standards 20 and 21 and serving also as a brace for the latter. At its upper end the lever 33 is connected by means of the link 35 to the under side of the plunger 29, suitable openings being provided in the table 22 to permit of these connections and of the reciprocatory movements thereof to take place. The lever 33 is oscillated about its pivotal suspension 34 by means of the connecting rod 36, pivotally connected thereto as at 37 at a point intermediate its ends, the connecting rod 36 having attached at its other end the eccentric strap 38, more clearly shown in Figure 8, engaging the eccentric 39, mounted upon the main driving shaft 40. The main driving shaft 40 is journaled in suitable bearings 41 in the standards 20 and 21 of the main frame.

The plunger 29 in the position shown in Figure 3 thus forms the temporary support for the vertical stack of articles delivered by the conveyor belt 23, and upon the reciprocation of the plunger 29 and its withdrawal to the left, as viewed in Figure 3, the stack of articles is permitted to advance down-

wardly until the lowermost article is supported upon the auxiliary table 42, conveniently formed integrally with the abutments 32 supporting the guides 30. Upon a reverse movement of the plunger 29, that is, in a direction to the right and into the position as shown in Figure 3, the lowermost article of the vertical stack is advanced to the right, and placed in operative position to the wrapper delivery mechanism and to the pockets of the tumbler mechanism to be hereinafter described.

At the right hand end of the main table 22, as seen in Figure 1, there are provided two vertically extending posts 43, which, with the posts 25, form the supports for an auxiliary frame mounted at the upper ends of the posts 25 and 43, the auxiliary frame comprising the longitudinally extending frame members 44 and 45, at each end of which are mounted the receptacles 46 and 47, in which are contained the stacks of sheets or wrappers with which the articles are to be enclosed. Suitable mechanism may be provided for discharging one sheet or wrapper at a time from each of the receptacles 46 and 47, and for delivering the wrappers to the wrapper delivery mechanism positioned substantially centrally between the receptacles 46 and 47. As the specific apparatus employed for thus discharging a single wrapper from each receptacle does not form part of this invention, it is not specifically illustrated, and will not be specifically described herein. It will be understood that either one or several such receptacles and their associated discharge mechanisms may be provided and associated with the wrapper delivery mechanism to be hereinafter described, according as it is desired to wrap each individual article in one sheet or wrapper or in several. In the embodiment illustrated, however, two such receptacles 46 and 47 are shown, and in the ensuing description it will be assumed that each individual article is to be encased in two wrappers, the material of which, as will be understood, may be of different character, according to the nature of the article to be wrapped, or according to the particular conditions desired to be met.

The sheet or wrapper feed mechanism for delivering the wrapper to the wrapping mechanism comprises a pair of conveyor chains 48 and 49, operating upon suitable pairs of sprocket wheels 50 and 51, the latter being mounted upon the driving shaft 52, suitably journaled in the upper frame members 44 and 45 of the auxiliary frame, and the former being rotatably mounted upon the shaft 53, suitably supported at the lower end of a pair of supporting posts 54 and 55 extending and suitably supported between the main table 22 and the frame members 44 and 45 respectively of the auxiliary

frame. The sprockets 51 are rigidly secured to the shaft 52, so as to rotate therewith and constitute the driving sprockets for the conveyor chains 48 and 49. The shaft 52 has mounted upon one end thereof a sprocket 56, which by means of the driving chain 57 is in driving connection with a suitable sprocket 58, mounted upon the main driving shaft 40 of the machine.

As will be more clearly seen in Figure 2, there is associated with the conveyor chains 48 and 49 a series of guides for guiding the wrappers or sheets carried in a downward direction by the chains 48 and 49. The guides comprise a pair of U-shaped members 59 and 60, slidably mounted and adjustably secured to the upright posts 54 and 55 respectively. The U-shaped guides 59 and 60 are adapted to engage the lateral edges of the sheets during their downward travel and effectively prevent displacement of the wrappers in a lateral direction. Moreover, it will be noted that the U-shaped members 59 and 60 are secured by means of the screws 61 extending through suitable slots 62 in the members 59 and 60, so as to permit of lateral adjustment of the U-shaped members in order to accommodate various widths of sheets or wrappers.

The chains 48 and 49 are provided at suitable intervals with lugs 63, more clearly shown in Figure 3, which positively engage the upper edge of the wrapper or wrappers in case more than one sheet is fed to the delivery mechanism, so as to positively carry the wrapper in a downward direction. In alternate spaced relation with the chains 48 and 49 are three vertical guide members 64, the relation of the latter with respect to the chains 48 and 49 being more clearly shown in the fragmentary sectional view in Figure 5. In this figure it will be noted that the adjacent edges or faces of the chains 48 and 49 and of the vertical guide member 64 do not lie in the same vertical plane and the relation with respect to one another is moreover such that a sheet or wrapper indicated as at 65 will be crimped or will be given what may in general terms be called a series of corrugations, the ribs of which extend in a vertical direction. The depth of the crimps or the degree of corrugation is made sufficient so as to give each sheet thus carried downwardly an inherent rigidity or resistance to bending about a horizontal axis.

As will be seen in Figure 3, there is provided a pair of vertically extending rods or bars 68 and 69 (more clearly shown in Figures 5 and 6), positioned respectively in the rear of the operative or delivery portions of the conveyor chains 48 and 49, for steadyng and guiding the chains during their downward travel. The guiding bars 68 and 69 are secured, by means of the brackets 70 and

71, respectively, to a cross bar 72, extending between and secured to the vertical posts 54 and 55. Set screws 73 and 74 in the brackets 70 and 71 respectively are adapted to lock the chain guiding bars 68 and 69 in position.

The vertical guide members 64 are secured to a cross member 66 (see Figs. 2 and 6) adjustably attached to the vertical posts 54 and 55 by means of the pins 66^a and 66^b, rigidly secured one at each end of the cross member 66 and in sliding engagement with the abutments 66^c and 66^d, rigidly secured to the posts 55 and 54 respectively. The cross member 66 with the guide members 64 mounted thereon may thus be moved toward or away from the operative portions of the chains 48 and 49 and may be locked in adjusted position by means of the set screws 66^e engaging the pins 66^a and 66^b. This arrangement permits the guiding bar 64 to be moved to a slight extent toward or away from the operative portions of the chains 48 and 49 so that the degree of crimping may be adjusted at will, commensurate with the character or stiffness of the sheet material employed.

Moreover, the guides 64 are preferably adjustably mounted upon the cross members 66, so that they may be placed in varying spaced relation with respect to one another, and with respect to the delivery chains 48 and 49, in accordance with the different widths of wrapper desired to be employed. For this purpose the vertical guide members 64 are slidably mounted upon the cross member 66, and each may be locked in position thereon by means of a suitable set screw 67, as is clearly indicated in Figure 6 of the drawings.

At the upper ends of the vertical posts 54 and 55, there is bridged a cross member 75 (see Figure 2), to which are rigidly secured two pairs of sheet guiding members, each pair comprising a downwardly extending guiding member 76 substantially in the same vertical plane with the vertical guide 64, as seen in Figure 5, and a second downwardly extending guide member 77, disposed to the rear of the member 76. The two pairs of guides 76 and 77 are in substantial vertical alignment with the U-shaped guides 59 and 60, and are adapted to guide the lateral edges of the sheet into the U-shaped guides 59 and 60, and into proper relation with the remaining guide members, such as the members 64. These two pairs of guides function to properly direct the sheets or wrappers from the sheet feeding mechanism, which discharges the latter from the receptacles 46 and 47 into the sheet delivery mechanism, and its associated guides above described.

At the lower ends of the vertical posts 54 and 55, there is bridged a cross member

78 (see Figures 3, and 7), to which are secured the vertically extending guides 79 and 80, and positioned substantially underneath the sprockets 50, so as to form a substantial continuation of the rear wall of the downwardly extending path of the sheets of wrappers. A rearwardly inclined guiding plate 81 is also bridged across the vertical posts 54 and 55, so as to form a 10 continuation of the front wall of the guiding path of the sheet delivering mechanism, the guides 79 and 80 and the guiding plate 81, functioning in effect as the guides for properly discharging the sheets as delivered 15 from the delivery mechanism, and for properly guiding the sheets into relation to the remaining mechanisms. A pair of V-shaped rests or supports 82 are secured to an inside portion of the main table 22, 20 and underneath a suitable opening therein, so as to be in position to receive and support temporarily the sheets or wrappers delivered. The rests 82 are adjustable in a vertical direction to accommodate various 25 lengths of wrappers. These rests 82 will be more specifically referred to hereinafter.

The particular apparatus for handling the article with an associated wrapper or wrappers will now be described in detail. 30 Upon one end of a shaft 83, journaled and driven in a manner to be hereinafter described in detail, is rigidly mounted a yoke 84 (see particularly Figures 2, 3 and 4), upon the respective ends of which are adjustably mounted two pairs of jaws 85 and 86. For this purpose the respective ends of the yoke 84 are machined to be received in suitable complementary slots, machined 35 in the jaws 85 and 86, as will be seen in 40 Figure 4, the respective jaws being secured to the yoke ends 84 by means of the cap screws 87 operating in suitable slots in the attaching portions of the jaws. As will be 45 seen in Figure 3, the jaws 85 and the jaws 86 of the two pairs may thus be adjusted toward or away from one another, so as to accommodate therebetween various thicknesses of articles desired to be packaged by the machine.

50 In order that the articles may be automatically held between the pairs of jaws, each jaw member is provided with a plate 88, conveniently upturned at its respective ends, and secured to the jaw member 85 by means of four pins 89 loosely engaged in a like number of openings in the jaw member 85, so as to permit relative motion between the gripping plates 88 and their associated 55 jaw members. Suitable springs 90 surround 60 each pin 89 and are interposed between the plates 88 and the associated jaw member, to tend to force the plates 88 of a given pair of jaw members toward each other. Thus, as 65 a single article is forced between the plates 88 of a given pair of jaws, the article will

be securely held in position by the spring-operated plates 88.

The shaft 83, with its associated yoke 84, and sets of jaws 85, and 86, is adapted to be intermittently rotated, as will be more clearly described hereinafter, and in a given position of rest the yoke 84 with its associated jaws will be found to take the position illustrated in Figures 2, 3 and 4, and as shown diagrammatically in Figure 13, in which it will be noted that a pair of jaws 85 are brought to rest in substantial alignment with the horizontal path given the articles by the plunger 29, as above described, and will be in a position adjacent to a sheet or wrapper delivered by the delivery mechanism above described, and temporarily resting upon the supports 82. Upon the continued operation of the plunger 29 the latter will force an article indicated as at 91 in a horizontal direction from left to right, and across the vertical sheet path as diagrammatically indicated in Figure 13 into the position indicated in Figure 14. During this operation the plunger 29 has caused the article 91 to engage the sheet 65 interposed in its path, and to force both the article 91 and the sheet 65 between the plates 88 of the pair of jaws 85, between which plates the article and its associated wrapper are securely held. This operation wraps the sheet about the article in a manner as indicated in Figure 14. During the operation just described, a device is operative to hold the sheet in proper relation to the article during the inward movement thereof, into the jaws 85. This device comprises a yoke 92, in the form of a bar sliding in a suitable slot 93 (see Figure 2), formed in the yoke 84. The sliding yoke 92 is retained in position in the slot 93 by means of a housing 94 (see Figure 3), bridged across the sliding yoke 92 and having interposed between the housing 94 and the sliding yoke 92 a spring 95, adapted to hold the yoke 92 in the slot 93. In order that sufficient resistance be offered by the sliding yoke 92 to its sliding movement within the slot 93, there is interposed between the spring 95 and the sliding yoke 92 a friction member 96, which may be of any suitable material, such as cork, for example. Upon one end of the sliding yoke 92, and extending transversely with respect thereto, is secured a holding member 97 (see Figure 3), and upon the other end of the sliding yoke 92 is mounted a corresponding holding member 98. The holding member 97 is adapted to co-operate with the jaws 85 and extends and moves therebetween, while the holding member 98 is adapted to operate similarly between the jaws 86.

The housing 94 is readily detachable so that the spring 95 may be easily replaced by one of a different stiffness or so that the

friction member 96 may be readily replaced by one of a different grade or character. In this manner the frictional effect upon the sliding yoke 92 may be conveniently varied or adjusted.

During the beginning of the operation above described, during which an article 91 and a wrapper or wrappers 65 are forced between a pair of jaws 85 and held by the associated spring-operated plates 88, the holding member 97 will have a position as indicated in Figure 3, in which it will be seen that the outer edge is substantially coincident with the plane of the outer edges of the plates 88. As the article 91 is forced to the right, as shown in Figure 3, and as diagrammatically indicated in Figure 13, the article 91 carries with it the wrapper 65 which is thereupon securely gripped between the holding members 97 and the article 91, the latter being positively moved by the action of the plunger 29. During this movement inwardly, the holding member 97 positively maintains the wrapper 65 in the desired alignment and relation with the article 91, so that the initial wrapping operation, as shown in Figure 14, is properly carried out. The degree of gripping of the sheet 65 between the holding member 97 and the article 91 is determined by the resistance offered to the sliding movement of the sliding yoke 92 by means of the spring 95, and the friction member 96 above described.

During these operations the rests or supports 82 may be relied upon to momentarily support the sheet 65, as shown in Figure 13, but it is to be understood that the employment of the rests 82 is not indispensable and that it may be preferable, by reason of the gripping action of the holding member 97, to dispense with the rests 82. It will also be understood that the lugs 63 on the conveyor chains 48 and 49 are properly spaced, and that the operation of the delivery chains is properly timed with respect to the action of the plunger 29, so that the wrapper 65 will be engaged by the article 91, and the holding member 97, at the proper relative positions thereof, without necessitating material stoppage of the wrapper. Furthermore, by reason of the corrugation of the sheet during its downward travel it will be sufficiently retained between the guiding members so as to avoid the possibility of the sheet dropping downwardly through the machine and thus to avoid also the necessity for the supports 82.

It will be noted that as the holding member 97 is pushed inwardly between the jaws 85, by reason of the advance of the article 91 therebetween, the complementary holding member 98, also mounted upon the sliding yoke 92, will be pushed outwardly between the jaws 86, and will be positioned in

readiness to be operated upon by a succeeding wrapper upon the rotation of the shaft 83, and yoke 84, through 180°, which rotation takes place immediately upon the insertion of an article in its wrapper between a pair of jaws.

As above mentioned, the shaft 83, and its associated yoke and sets of jaws, are rotated intermittently through 180°. The mechanism for obtaining such intermittent rotation will now be described in detail: The shaft 83 is rotatably mounted in a bushing 99, which is mounted for vertical adjustment in a bracket 100 mounted upon the main table 22 of the machine (see Figures 4 and 4a). The bracket 100 is provided with a vertical slot 101, in which is received a vertically extending rib 102, integrally formed with the bushing 99, so as to guide the bushing 99 throughout its range of adjustment. A hand screw 103 is in threaded engagement with the bushing 99, and is held from vertical movement by means of a collar 104, suitably secured at its lower end and engaging the countersunk opening 105 in the under side of the bracket 100. Cap screws 106, operating in vertically extending slots in the bracket 100, are provided for locking the bushing 99 in its adjusted position.

As before noted, the jaws 85 and 86 are adjustable relatively to one another to accommodate various thicknesses of articles to be wrapped, and the vertical adjustment of the bushing 99 and hence of its associated shaft 83 and jaw-carrying yoke 84, makes it possible to raise and lower the latter, so that the lowermost jaw, as viewed in Figure 3, will be in alignment with the plane of the auxiliary table 42, from which the articles are forced by the plunger 29, between the jaws.

Referring now more particularly to Figures 2, 11 and 12, it will be seen that the shaft 83 is driven by means of the gear 107 mounted at its exterior end, and engaging the idler gear 108, which places the driving gear 107 in driving engagement with the main driving gear 109, mounted upon a stud shaft 110, suitably mounted in the housing 111, which is conveniently made to encase this train of driving gears (see also Figure 8). The intermediate gear 108 is rotatably mounted upon a stud 112, secured to a bracket 113, pivoted upon a reduced portion 114 of the bushing 99. The bracket 113 is provided with an extension 116, which is slotted as at 117, so as to engage the pin 118, rigidly fixed in the housing 111 (see Figure 11). The bracket 113, carrying the intermediate gear 108, is thus free to swing about the axis of shaft 83, and in the position illustrated the relation between the several parts is shown as it exists with the shaft 83 adjusted to its uppermost position.

When, however, it is desired to lower the shaft 83 by means of the adjusting screw 103, as above described, the bracket 113 will be swung outwardly about the axis of the shaft 83, and will be guided in its outward swing by the pin 118 engaging the slot 117. The proper driving relation of the train of gears is thus automatically maintained for each position of adjustment of the shaft 83.

10 The intermittent rotation of the shaft 83 is attained by means of what may be termed a Geneva stop motion, and, in the embodiment illustrated, the gear 109 is intermittently rotated throughout a sufficient extent to bring about the desired rotation of the shaft 83, and its associated two pairs of jaws. As will be seen from Figures 8 and 11, there is secured to the face of the gear 109, as by means of the cap screws 119, what will be termed the follower plate 120, which is provided with four radially extending channels 121, spaced 90° apart and formed by the ribs 122 integrally formed in the face of the plate 120. The four channels 121 extend inwardly to a central circular space 123.

15 20 25

Cooperating with the channels 121 in the follower plate 120 is a driving member comprising the cam disk 124, having mounted upon its face adjacent to the follower plate 120 a driving roller 125 adapted for engagement with and passage through the channels 121 in the follower plate 120. The cam disk 124 is mounted upon an auxiliary shaft 126, suitably journaled in the standards 20 and 21 of the machine, and driven from the main shaft 40 and at the same speed therewith, by means of the sprocket and chain connection indicated at 127. The gear 109 is preferably made twice the diameter of the driving gear 107 upon the shaft 83 and the driving mechanism just described is adapted to cause a rotation of the gear 109 of 90°, which will correspond to a rotation of the gear 107, and hence of the shaft 83 and the yoke 84 of 180°. The follower plate or disk 120 is provided with four notches 128, with which is adapted to operate a locking member 130 mounted upon the end of an arm 131, which is pivoted upon the stud 132, suitably secured to the standard 21 of the main frame. A spring 133, connected to the arm 131, urges the latter, and hence also the locking member 130, toward the periphery of the follower disk 120. A stud 134 in the arm 131 carries a cam roller 135, which is adapted to be engaged by the periphery of the cam disk 124, and to control the position of the locking member 130, with respect to the slots 128 in the periphery of the follower disk.

Upon rotation of the auxiliary shaft 126 in a clockwise direction, as viewed in Figures 11 and 12, the locking member 130

having retained the follower disk 120 in the position shown by engagement with one of the locking slots therein, the driving roller 125 will enter one of the channels 122, as indicated, and will cause a clockwise rotation of the follower disk 120, the simultaneous rotation of the cam 124 having raised the locking member 130 out of locking engagement with the follower disk. The cam 124 retains the locking member 130 in the position shown in Figure 12 until the follower disk 120 has passed through a rotation of 90°, at which time the driving roller 125 will be moved out of the driving channel 121 and into a central circular space 123. At the same time the cam 124 permits the locking member 130 to come into engagement with the next succeeding locking slot 128 in the follower disk, whereupon the latter is locked in the stationary position 85 until the driving roller 125, in continuing its rotation about the axis of the auxiliary shaft 126, is again ready for driving engagement with the next succeeding radial driving channel 121.

90 95 100 105

The extent of the driving channels 121 and the throw of the driving roller 125 are so proportioned that the follower disk will be in motion for approximately 270° of the rotation of the driving shaft 126, and will be at rest during the remaining 90° of its rotation. The resultant action upon the two pairs of jaws mounted upon the yoke 84 will be the rotation thereof of 180° throughout a substantial portion of a single rotation of the main driving shaft, and a position of rest throughout a minor portion of a rotation of the main driving shaft.

110 115 120 125 130

Hence it will be seen that the article and its associated wrapper or wrappers will be thrust into a pair of jaws 85 during the pause in the clockwise rotation of the yoke 84, and its two sets of jaws, and that immediately thereafter the clockwise rotation of the two sets of jaws takes place so as to carry the inserted article and its wrapper through 180°, and into position to be operated upon by the ejector. During such rotative movement the guiding plate 31 (see Figures 3 and 14) functions to smooth or fold the unfolded end of the wrapper into the position indicated at 65^a in Figure 14. As the rotation throughout the 180° approaches its end, the wrapper end 65^a (see Figures 3 and 15) is engaged by a pivotally mounted and spring-pressed tightening member 136. The member 136 is preferably composed of a material like leather, for example, which may exert a substantial frictional action upon the wrapper, and is mounted upon a plate 137, which is pivotally mounted upon the pin 138 in the bracket 139 mounted upon the auxiliary frame 140, secured to the vertical posts 43. A lever extension 141, rigidly secured

to the plate 137, is engaged by a spring 142, so as to urge the tightening member 136 in a clockwise direction about the pin 138. The action of the tightening member 136 (see Figures 3 and 15) is to draw the wrapper 65 taut about the article 91, the wrapper end 65^a assuming in general the position indicated in Figure 15 and being gripped between the member 136 and the 10 jaw 85 during the ejecting movement given the article. The article 91 is now ready to be ejected from the jaws, the latter having completed their rotation of 180°.

The ejector comprises a bar 143 (see Figures 2, 4, 9 and 10) mounted for reciprocation between the two jaws of the pair that happen to be positioned at the right as viewed in Figure 3, for example. The ejector 143 is mounted upon a cross head 144, 20 in sliding engagement with two guiding bars 145 and 146, suitably mounted within the main opening in the main table 22 of the machine. The cross head 144 is connected by means of the link 147 to one end of a lever 148 fulcrumed as at 149 upon the auxiliary driving shaft 126, and connected at its lower end to the connecting rod 150 adapted to be reciprocated by means of the eccentric 151, to which it is connected by 30 means of the eccentric strip 152. The eccentric 151 is mounted upon the main driving shaft 40 of the machine.

The eccentric 151 is so positioned upon the shaft 40 that it causes a forward movement 35 of the ejector bar 143, as soon as the rotation of the yoke 84 and its associated jaws through 180° is substantially completed. Thus in Figure 10 the ejector 143 is shown in the position in which it is about to begin 40 its ejecting movement between the jaws 86 of the yoke 84, and in Figure 9 the ejector 143 is illustrated in its position at the beginning of its return stroke, the return being so timed that it assumes its initial position by passing between the two pairs of 45 jaws 85 and 86, during their rotation, rather than between the jaws of a single pair, as was the case during its ejecting operation.

Upon being ejected from the right-hand 50 pair of jaws, as above described, the article 91 (see Figure 15) is forced between a pair of blades 140 and 153 and the wrapper end 65^a folded into the position shown in Figure 16. The remaining tucking operations 55 now take place, but as these form no part of this invention they will be but briefly referred to herein.

A pair of tucking blades 154 (see Figures 3 and 4) are vertically reciprocated by means 60 of the bars 155 suitably guided in the main frame and operated by means of the link 156, pivoted upon the auxiliary shaft 126 and oscillated about its pivot in proper timed relation with respect to the other mechanisms 65 by means of a cam 157 operating upon the

cam roller 158 mounted upon the arm 156. These blades 154 tuck in the two upper ends of the wrapper, whereupon the rotary tucking blades 159, mounted upon the shaft 160 and driven by means of a sprocket 161, operate to complete the next step of the tucking operation, whereupon the stationary folding blades 162 complete the folding up of the tucked ends of the wrapper and deliver the completely wrapped article to the conveyor 70 belt 163 operatively positioned at the discharge end of the machine. These latter operations are well understood in the art, and are therefore not set forth in detail herein.

It will thus be seen that there has been 80 provided in this invention an apparatus in which the several objects above pointed out, as well as others, have been obtained and in which many advantages have been achieved. It will further be noted that an apparatus 85 has been provided which is capable of extremely high speed of operation by reason of the positively acting wrapper delivery mechanism employed, and by reason of the relative timing allotments, as determined by 90 the drying mechanisms above pointed out to the various functions performed by the article handling jaws or mechanisms. As hereinbefore pointed out, the rotation of the sets of jaws through the desired extent of 95 180°, which is the case where only two sets of jaws are employed, takes place during a substantial or major part of a single revolution of the main driving shaft. The minimum time space allotment has been made in 100 which the operations take place while the parts are stationary, so as to permit a greater time interval during which the 105 rotational movements may take place, all as related to a single revolution of the main driving shaft. Hence a higher rate of speed of the main driving shaft is made possible and a corresponding increase in the capacity of the apparatus. It will furthermore be noted 110 that this invention has provided an apparatus which is of positive action throughout, and which is distinctly practical in nature.

As many possible embodiments may be 115 made of the above invention, and as many changes might be made in the embodiment above set forth, it is to be understood that all matter herein set forth is to be interpreted as illustrative and not in a limiting sense.

I claim:

1. In apparatus of the class described, in combination, an intermittently movable work carrier having a plurality of article-receiving means, each comprising a pair of jaws for receiving therebetween an article, driving means for moving said work carrier, means for adjusting the jaws of each article-receiving means on said carrier relatively to one another to accommodate articles of various thicknesses, means for mov- 120
125
130

ing an article and a wrapper along a predetermined fixed path into one of said receiving means and between the jaws thereof, and means for adjusting said work carrier 5 with respect to said predetermined path to align the jaws of said receiving means with said path upon a pause in the movement of said carrier, said adjusting means being operable without disturbing the driving 10 means for said work carrier.

2. In apparatus of the class described, in combination, article receiving means, means for moving an article into said receiving means, a moving delivery chain for positive- 15 ly carrying a wrapper into the path of said article, whereby said wrapper is partially folded around said article as said article is moved into said receiving means and means operative upon a wrapper and adapt- 20 ed to give the latter a greater resistance to bending thereof than is inherent in the wrapper itself.

3. In apparatus of the class described, in combination, article receiving means, means 25 for moving an article into said receiving means, a delivery chain provided with means for engaging a wrapper for moving said wrapper into the path of said article, whereby said wrapper is partially folded 30 around said article as said article is moved into said receiving means, means for crimping said wrapper to prevent bending thereof, and means for operating said chain in timed relation to said moving means.

35 4. In apparatus of the class described, in combination, article receiving means, means for moving an article into said receiving means, means for positioning a wrapper in the path of said article, whereby said wrapper is folded around said article as said article is moved into said receiving means, means associated with said article receiving 40 means and having less width than the thickness of said article for engaging and holding said wrapper in relation to said article as said article and said wrapper are moved into said receiving means and separate means adapted to by-pass said holding means for 45 ejecting said article with said wrapper from said article-receiving means.

5. In apparatus of the class described, in combination, a pair of article-receiving means, means for moving an article into one of said receiving means, means for successively positioning said pair of receiving 55 means to said article-moving means, means for positioning a wrapper in the path of said article whereby said wrapper is partially folded around said article as the latter is moved into one of said receiving means, a pair of members each associated with one of said receiving means and each adapted to engage and hold said wrapper in relation to said article and to be moved 60 therewith throughout the extent of move- 65

ment of said article into said receiving means, means rigidly connecting said pair of members whereby the movement of one of said members by said article positions the other in the other receiving means in wrapper-engaging position and a substantially continuously moving ejector acting in advance of the other of said members and in the said other receiving means for ejecting an article with its associated wrapper there- 70 75

6. In apparatus of the class described, in combination, a pair of article-receiving means, means for moving an article into one of said receiving means, means for successively positioning said pair of receiving means to said article-moving means, means for positioning a wrapper in the path of said article whereby said wrapper is partially folded around said article as the latter is moved into one of said receiving means, a pair of members each associated with one of said receiving means and each adapted to engage and hold said wrapper in relation to said article and to be moved therewith throughout the extent of movement of said article into said receiving means, means rigidly connecting said pair of members whereby the movement of one of said members by said article positions the other in the other receiving means in wrapper-engaging position, positively acting frictional means for retarding the movement of said pair of members to insure positive gripping of said wrapper and an ejector acting independently of said wrapper engaging means for ejecting an article with its associated wrapper from one of said receiving means. 80 85 90 95 100

7. In apparatus of the class described, in combination, article receiving means, means for moving an article into said receiving means, means for positioning a wrapper in the path of said article, whereby said wrapper is folded around said article as the latter is moved into said receiving means, means associated with said receiving means for engaging and gripping said wrapper to hold the latter in relation to said article, means acting independently of said gripping means for subsequently ejecting said article with said wrapper from said receiving means, and means for adjusting the gripping action of said wrapper engaging and gripping means. 105 110 115 120

8. In apparatus of the class described, in combination, a pair of article-receiving means, means for moving an article into one of said receiving means, means for successively positioning said pair of receiving means to said article-moving means, means for positioning a wrapper in the path of said article whereby said wrapper is partially folded around said article as the latter is moved into one of said receiving means, a 125 130

pair of members each associated with one of said receiving means and each adapted to engage and hold said wrapper in relation to said article and to be moved therewith through-
5 out the extent of movement of said article into said receiving means, means rigidly connecting said pair of members whereby the movement of one of said members by said article positions the other in the other 10 receiving means in wrapper-engaging position, and an ejector acting in advance of said member and in the other of said receiving means for ejecting an article with its associated wrapper therefrom.

15 9. In apparatus of the class described, in combination, article-receiving means, means for moving an article into said receiving means, means forming a path for guiding a wrapper into the path of said article, means 20 for moving a wrapper along said path, and means associated with said guiding means for temporarily crimping said wrapper in the direction of said path.

10. In apparatus of the class described, 25 in combination, article-receiving means, means for moving an article into said receiving means, guiding means for guiding a wrapper into a position interposed between said moving means and receiving 30 means whereby said wrapper is folded around said article as the latter is moved into said receiving means, means for moving a wrapper along said guiding means, and means for making a plurality of corrugations in said wrapper and extending 35 in the direction of movement of said wrapper, said means being operative prior to the positioning of said wrapper between said receiving means and said moving means.

40 11. In apparatus of the class described, in combination, article-receiving means, means for moving an article into said receiving means, means forming guides for conducting a wrapper to an interposed position between said moving means and said receiving means, and a plurality of bars associated with said guiding means and arranged out of alignment with one another for crimping said wrapper during its movement along said guiding means.

45 12. In apparatus of the class described, in combination, article-receiving means, means for moving an article into said receiving means, means forming a guide for conducting a wrapper to an interposed position between said moving means and said receiving means, a conveyor chain associated with said guiding means for positively moving a wrapper into said interposed position, and a pair of bars one on each side of said chain and placed out of alignment therewith for making a crimp in said wrapper interposed between said chain and said pair of bars.

50 13. In apparatus of the class described,

in combination, article-receiving means, means for moving an article into said receiving means, a pair of guides for conducting a wrapper to an interposed position between said receiving means and said moving means, and a conveyor chain interposed between said pair of guides and positioned out of alignment therewith for positively moving said wrapper interposed between itself and said pair of guides, said chain and said pair of guides placing a crimp in said wrapper during its movement along said guides.

14. In apparatus of the class described, in combination, article-receiving means, means for moving an article into said receiving means, guiding means including a pair of bars and means interposed between said bars and placed out of alignment therewith for placing a crimp in a wrapper interposed therebetween, said guiding means acting to guide a wrapper to a position interposed between said article-receiving means and said article-moving means, means for moving a wrapper along said guiding means, and means for varying the extent to which said pair of bars and said interposed means are out of alignment, thereby to vary the degree of crimping of said wrapper.

15. In apparatus of the class described, in combination, article-receiving means, means for moving an article into said receiving means, a pair of bars for guiding a wrapper to a position interposed between said receiving means and said moving means, a conveyor chain interposed between said bars and out of alignment therewith for crimping a wrapper interposed between said bars and said chain and for moving said wrapper to said interposed position, and means for varying the extent to which said bars and said chain are out of alignment thereby to vary the degree of crimping of said wrapper.

16. In apparatus of the class described, in combination, article-receiving means, means for moving an article into said receiving means, a pair of spaced U-shaped bars for engaging the lateral edges of a wrapper and for conducting said wrapper to a position interposed between said receiving means and said moving means, means for moving said wrapper along said guiding bars to said interposed position, means for distorting said wrapper out of its plane to give said wrapper an inherent rigidity against bending, and means for varying the spaced relation of said two U-shaped bars for accommodating various widths of wrapper.

17. In apparatus of the class described, in combination, a plurality of article receiving means, means for moving an article into one of said receiving means, means for positioning a wrapper in the path of said article whereby said wrapper is folded around said article as said article is moved into

said one receiving means, a discharge channel, a main driving shaft, means mounting said plurality of article receiving means for intermittent movement thereof to position 5 one of said receiving means in operative relation to said article moving means and another of said receiving means in operative relation to said discharge channel, driving connections between said main driving shaft 10 and said mounting means for moving said mounting means and its associated plurality of receiving means throughout a major portion of a revolution of said main driving shaft and for permitting said mounting 15 means to be at rest for a minor portion of a revolution of said driving shaft, and an ejector driven from said main shaft for ejecting said article and its associated wrapper from one of said holding means and 20 into said discharge channel during the pause in the movement of said mounting means.

18. In apparatus of the class described, in combination, a rotatable yoke, a pair of article receiving means, one mounted upon 25 each end of said yoke and each comprising a pair of article holding jaws, means for moving an article into one of said receiving means, means operative upon the completion of the operation of said moving means 30 for rotating said yoke to position said other receiving means in operative relation to said article moving means, and a substantially continuously moving ejector timed to make its ejecting stroke upon the completion of 35 said rotary movement of said yoke and operating between the jaws of said first mentioned article receiving means to eject the article therefrom and to make its return stroke during a subsequent rotary movement 40 of said yoke and between said pair of article receiving means.

19. In apparatus of the class described, in combination, a plurality of article receiving means, means for moving an article 45 into one of said receiving means, means for positioning a wrapper in the path of said article whereby said wrapper is folded around said article as said article is moved into said one receiving means, a discharge 50 channel, a main driving shaft, means mounting said plurality of article receiving means for intermittent movement thereof to position one of said receiving means in operative relation to said article moving means 55 and another of said receiving means in operative relation to said discharge channel, driving connections between said main driving shaft and said mounting means for moving said mounting means and its associated plurality of receiving means 60 throughout a major portion of a revolution of said main driving shaft and for permitting said mounting means to be at rest for a minor portion of a revolution of said 65 driving shaft, an ejector for ejecting said

article and its associated wrapper from one of said holding means and into said discharge channel during the pause in the movement of said mounting means, and a driving connection between said main driving shaft and said ejector for giving said ejector a substantially continuous movement. 70

20. In apparatus of the class described, in combination, a plurality, of article receiving means, means for moving an article into one of said receiving means, means for positioning a wrapper in the path of said article, whereby said wrapper is folded around said article as said article is moved into said one receiving means, separate mechanism for completing the wrapper operation, a main driving shaft, means mounting said plurality of articles receiving means for intermittent movement thereof to position one of said receiving means in operative relation to said article moving means and another of said receiving means in operative relation to said completing mechanism, driving connections between said main driving shaft and said mounting means for moving said mounting means and its associated plurality of receiving means throughout a major portion of a revolution of said main driving shaft and for permitting said mounting means to be at rest for a minor portion of a revolution of said driving shaft, and an ejector driven from said main shaft for ejecting said article and its associated wrapper from one of said holding means and into said completing mechanism during the pause in the movement of said mounting means. 80 85

21. In apparatus of the class described, in combination, a rotatable yoke, a pair of article receiving means each mounted upon one end of said yoke, a main driving shaft, driving connections between said driving shaft and said rotatable yoke for giving said yoke a rotation of 180 degrees during a major portion of a revolution of the main shaft and for holding said yoke at rest during a minor portion of said revolution of said main shaft, means for moving an article into one of said receiving means and operative while said yoke is at rest, means positioning a wrapper in the path of said article whereby said wrapper is folded around said article as the latter is moved into said receiving means, separate completing mechanism for tucking the ends of said folded wrapper, said yoke being interposed between said article moving means and said completing mechanism, and an ejector operated from said main shaft and operative to eject said article and its wrapper from said receiving means and into said completing mechanism after a subsequent rotation of said yoke and during the following pause thereof. 100 105 110 115 120 125

22. In apparatus of the class described, 130

in combination, a rotatable yoke, means for driving said yoke, a pair of article receiving means, each mounted upon one end of said yoke and each comprising a pair of jaws for holding said article, means for adjusting the jaws of each receiving means relatively to one another to accommodate articles of various thicknesses, means for moving an article and a wrapper along a predetermined fixed path into one of said receiving means, and means for adjusting said yoke with respect to its driving means to align said adjustable jaws of said receiving means with said moving means.

15 23. In apparatus of the class described, in combination, a rotatable yoke, a pair of article receiving means each mounted upon one end of said yoke and each comprising a pair of relatively adjustable jaws between which an article may be received, means for moving

an article and a wrapper along a predetermined path into one of said receiving means, a main driving shaft, driving connections between said driving shaft and said rotatable yoke for intermittently rotating said yoke and for successively positioning said receiving means in operative relation to said article and wrapper moving means, and means for adjusting said rotatable yoke with respect to said predetermined path to align said adjustable jaws of said receiving means with said moving means, said yoke adjusting means being operable without disturbing the driving connections between said yoke and said main driving shaft.

In testimony whereof, I have signed my name to this specification this 8th day of September.

MILFORD B. FERGUSON.
